UNITED STATES PATENT OFFICE.

JOHN NORTHON, OF CLARE, MICHIGAN.

ROAD LEVELER.

Application filed April 8, 1921. Serial No. 459,541.

To all whom it may concern:

Be it known that I, JOHN NORTHON, a citizen of the United States of America, residing at Clare, in the county of Clare and State of Michigan, have invented certain new and useful Improvements in Road Levellers, of which the following is a specification.

My present invention relates generally to road graders, and more particularly to certain improvements in road graders of the type and construction described and claimed in my Patent 1,329,543 dated February 3, 1920.

My present improvements aim to provide a road grader of the above type having a riding device which will provide for proper steering as well as adjustment in the several respects to be hereinafter particularly pointed out.

My improvements also aim to provide a novel form of traction shoe whose wear surface may be readily renewed and whose adjustment, to raise and lower the blades, may be readily and effectively accomplished.

In the accompanying drawings which illustrate my present invention and form a part of this specification,

Figure 1 is a perspective view of the complete grader,

Figure 2 is a side view of the riding device looking at the right side,

Figure 3 is a similar view looking at the left side,

Figure 4 is a detail view of the central portion of the axle with its bolster,

Figure 5 is a plan view of the riding device,

Figure 6 is a detail perspective view of one of the traction shoes.

Figure 7 is a detail section of the central portion of the axle with its bolts taken at right angles to Figure 4.

Figure 8 is a longitudinal section showing the brake shoe.

Figure 9 is a bottom plan view of Figure 4, and,

Figure 10 is a detail longitudinal section along the block between the reach bars.

Referring now to these figures and particularly to Figure 1 my invention has to do with road graders of the type embodying a central beam 10 projecting parallel with and between side beams 11 and elevated slightly above these side beams by virtue of crowned cross braces 12 providing

for adjustment of the spacing of the side beams 11. The side beams 11 travel on the roadway surface in use by virtue of shoes 13 adjustable by connections including hand wheels 14, and the side beams also have hitch plates 15 for a chain hitch 16 adapting the grader to attachment in operation with either a tractor or draft animals.

The center beam 10 and side beams 11 cooperate in the support of inclined blade supporting bars 17, arranged in staggered relation, including a rear bar 18, for the support of the planer blades 19 and the grader blade 20, and for the purpose of the bar 18 and the grader blade 20, the rear end of the center beam 10 extends rearwardly beyond the rear ends of the side beams 11.

According to my present improvements traction wheels 21 are disposed upon opposite sides of the rearwardly projecting portion of the center beam 10 and are mounted upon opposite ends of a transverse axle 22, this axle being provided with a central bolster 23 having an upstanding king pin 24 and having depending spaced knees 25, the latter of which extend upon opposite sides of the rear end of the center beam 10 and have convex inner faces as seen in Figure 9 permitting the axle to be turned with respect to the beam with the king pin 24 as its axis of swinging movement.

For this purpose a reach 26 is utilized, preferably formed of a pair of parallel bars whose forward ends are curved downwardly and have transverse apertures 27 to receive a transverse pivot bolt 28 pivotally connecting this forward downturned end of the reach to the center beam 10 intermediate the ends of the latter. The bars composing the reach 26 are spaced apart by blocks including a rear block 29, the latter having a vertical opening to receive the king pin 24 and being also provided with a laterally projecting pin 30 on which a grooved guide roller 31 is journaled at one side of the rear end of the reach.

Opposite the center block of the reach are secured spaced upstanding quadrants 32 engaged by the latch mechanisms 33 of a pair of control levers 34 and 35 having handles upstanding in front of the driver's seat 36 secured on a frame 37 in turn mounted upon and balanced above the axle 22.

The lower end of lever 34 has connected thereto the forward upper end of a chain 38 extending rearwardly and downwardly

around the guide roller 31 and secured at its rear lower end to the rear end of the center beam 10 as indicated in Figure 1.

The lower end of lever 35 is pivotally connected to the forward end of a steering arm 39 whose rear end is pivotally connected to one of the supporting clamps 40 of the seat frame 37.

The center block 41 of the reach, through which the quadrants 32 are secured and through which levers 34 and 35 are fulcrumed, is also provided with a rearwardly projecting arm 41^a spaced below the reach as shown in Figure 10 to receive thereon and movably support the cross bar of a U-shaped frame 42 whose rear ends are secured to the clamps 40.

In practice it is well known that road graders or road maintainers of the general type first above described and as shown in my previous patent swerve to the right or left too readily and easily unless some form of guide is utilized in connection therewith, and it is equally well known that when properly guided it is often desired by the operator to swerve the rear end of the grader to the right or to the left without changing the hitch on the draw chain. My present improvements by adding the traction and guide wheels 21 provide for the effective guiding of the scraper to avoid undesirable swerving and also by virtue of the fact that the operator by shifting lever 35 may swing the axle 22 around the center formed by the king pin 24, it is obvious swerving of the rear end of the grader may be effected whenever this becomes either desirable or necessary.

It is also obvious that in the use of the grader with my present improvements the operator by manipulating lever 34 may raise or lower the rear end of the beam 10 and in this way regulate the depth of planing of the grader or leveler.

In carrying out my present invention it will be noted that as the seat 36 and seat frame 37 are supported on and balanced above the axle 22, all of the weight of the operator will be carried by the traction wheels 21, thus holding the latter more stable and steady upon the ground and at the same time avoiding any additional weight or bearing on the ground engaging shoes 13 of the side beams 11.

Referring now to the shoes 13, it will be noted from Figure 6 that each shoe has an upper bracket 45 with which the lower end of the adjusting screw 46 of its hand wheel 14 is connected, and each shoe has a forward bracket 47 whose upstanding portion is provided with a vertically elongated slot 48 receiving therethrough a transverse bolt 49 of the respective side beam 11. The shoe also provides for the reception of a detachable steel sole plate 50 and by its particular

mounting, does away with all springs while the slot in bracket 47 permits the front end of the shoe to seek its level when the adjusting screw is turned up or down.

I claim:

1. In combination with a road scraper having a rearwardly projecting center beam, a reach having a pivotal connection at its forward end with the center beam and projecting at its rear portion above and approximately parallel with the beam, an axle extending transversely between the rear ends of the beam and reach, traction wheels mounted upon the ends of the said axle at opposite sides of the beam, a seat frame and seat supported on and balanced above the said axle, a bolster centrally of the axle having an upstanding king pin on which the rear end of the reach is journaled, a pair of knees depending from the bolster at opposite sides of the beam and having inner convex faces, a roller journaled at one side of the rear end of the reach, a steering arm secured to the axle at the opposite side of the reach, a pair of control levers fulcrumed at opposite sides of the reach intermediate the ends of the latter and having handles upstanding in front of the seat, a pivotal connection between one of said levers and the said steering arm, and a flexible connection secured at one end to the other lever and projecting rearwardly and downwardly around the said roller, the lower rear end of the last mentioned connection being secured to the rear end of the said beam. 100

2. In a road scraper having a frame including a center beam, a reach pivotally connected at its forward end to the said beam to swing in a vertical plane, an axle pivoted at its center to the rear end of the reach, wheels on the ends of the said axle, a lever fulcrumed on the reach and having connection with the axle at one side of the reach to control swinging movement of the former, a seat and frame supported on the axle, and a second lever fulcrumed on the reach, having a flexible connection with the rear end of the beam. 110

3. In a road scraper having a frame including a center beam, a reach pivotally connected at its forward end to the said beam to swing in a vertical plane, an axle pivoted at its center to the rear end of the reach, wheels on the ends of the said axle, a lever fulcrumed on the reach and having connection with the axle at one side of the reach to control swinging movement of the former, a seat and frame supported on the axle, and means supported by the reach and engaging the rear end of the said beam for raising and lowering the latter. 120

4. In a road scraper having a rearwardly projecting center beam, a reach pivoted at its forward end to the beam, an axle across the rear portion of the beam pivotally con- 130

- nected to the rear end of the reach, wheels mounted on the axle at opposite sides of the beam, a seat and seat frame supported on and balanced above the axle, connections for 5 raising and lowering the rear end of the beam with respect to the reach, and connections for swinging the axle with respect to the rear end of the reach for steering purposes.
- 10 5. In a road scraper having a rearwardly projecting center beam, a reach pivoted at its forward end to the beam, an axle across the rear portion of the beam pivotally connected to the rear end of the reach, wheels 15 mounted on the axle at opposite sides of the beam, a seat and seat frame supported on and balanced above the axle, connections for raising and lowering the rear end of the beam with respect to the reach, and 20 connections for swinging the axle with respect to the rear end of the reach for steering purposes, said connections including manual control levers mounted on the reach and upstanding forwardly of the seat.
- 25 6. In a road scraper having a center beam, a reach extending along and above the rear portion of the beam and having pivotal connection at its forward end thereto, an axle extending between the rear ends of the beam 30 and reach and pivotally connected at its center to the reach, a seat supported by the axle, wheels mounted on the ends of the axle, and means mounted on the reach for controlling vertical swinging movement of 35 the beam and horizontal swinging movement of the axle.
7. In a road scraper having a center beam, a reach extending along and above the rear portion of the beam and having pivotal connection at its forward end thereto, an axle 40 extending between the rear ends of the beam and reach and pivotally connected at its center to the reach, a seat supported by the axle, wheels mounted on the ends of the axle, said reach having a side roller adjacent 45 to its rear end, a flexible connection extending around the roller and secured at its lower end to the rear portion of the beam, a control lever to which the upper forward end of the flexible member is connected, and 50 means for controlling swinging movement of the axle with respect to the reach as described.
8. In a road scraper having a center beam, a reach extending along and above the rear 55 portion of the beam and having pivotal connection at its forward end thereto, an axle extending between the rear ends of the beam and reach and pivotally connected at its center to the reach, a seat supported by 60 the axle, wheels mounted on the ends of the axle, means for controlling vertical swinging movement of the beam with respect to the reach, a steering arm secured to the axle at one side to the reach, and a lever 65 mounted on and upstanding above the reach and operatively connected to the said steering arm of the axle as described.

In testimony whereof I have affixed my signature.

JOHN NORTHON.
